Attorney

UNITED STATES PATENT OFFICE.

PAUL SZYDLOWSKI, OF DETROIT, MICHIGAN.

LOCK.

Application filed May 8, 1922. Serial No. 559,224.

To all whom it may concern:

Be it known that I, PAUL SZYDLOWSKI, citizen of the United States, residing at Detroit, county of Wayne, State of Michigan, have invented a certain new and useful Improvement in Locks, and declare the following to be a full, clear, and exact description of the same, such as will enable others skilled in the art to which it pertains to make and use the same, reference being had to the accompanying drawings, which form a part of this specification.

My invention relates to permutation locks shown in the accompanying drawings and more particularly described in the following specification and claims.

The object of my invention is to provide a simple and inexpensive lock of the character described which may be employed as a steering wheel lock for automobiles, a tire lock, door lock or the like.

One of the objects of the invention is to provide a device having relatively few parts, simple in its construction and operation and which will not readily get out of order.

With the foregoing and other objects in view which will appear as the description proceeds, the invention further resides in the combination and arrangement of parts and in the details of construction hereinafter described and claimed, it being understood that changes may be made in the precise embodiment of the invention herein disclosed without departing from the spirit of the same.

In the drawings accompanying this specification:

Figure 1 is a side elevation of a lock barrel showing it connected with a fragment of a chain that it may be used as a tire lock.

Figure 2 is a vertical cross-sectional view taken on or about line 2—2 of Figure 1, showing the bolt in its locked position.

Figure 3 is a perspective view of the bolt removed from the barrel.

Figure 4 is a cross-sectional view taken on or about line 4—4 of Figure 2 through the tumblers and bolt, the latter being in its "locked" relation.

Figure 5 is a detailed perspective view of the driving disc which when assembled is keyed to the bolt, that it may be rotated thereby.

Figure 6 is a perspective view of one of the tumblers carrying a projecting pin

adapted to be acted upon by the driving disc.

Figure 7 is a perspective view of another tumbler in which the tumbler shown in the preceding view is sleeved.

Figure 8 is a perspective view of a tumbler adapted to receive the tumbler shown in Figure 7.

Figure 9 is a cross-sectional view taken on or about line 9—9 of Figure 2.

Figure 10 is a perspective view of the washer keyed to the bolt provided with a lug adapted to enter any of the several serrations or grooves formed in the end of the lock casing.

Figure 11 is a fragmentary perspective view of the lock casing showing it provided with a series of serrations to receive the lug of the washer shown in Figure 2,—the serrations being spaced apart at one point to indicate the "starting position."

Figure 12 is a perspective view of a drag-spring lodged in a groove in the enlarged head of the respective tumblers shown in Figures 6 and 7.

Figure 13 is a side elevation of a helical spring lodged between the washer shown in Figure 10 and the end wall of the graduated cap secured to the end of the bolt and overlapping the lock casing.

Figure 14 is a vertical cross-sectional view of the lock showing the bolt in its "unlocked" position.

Figure 15 is a cross-sectional view taken on or about line 15—15 of Figure 2 showing the bolt in its locked position.

Figure 16 is a similar cross-sectional view taken on or about line 16—16 of Figure 14 showing the bolt in its unlocked position.

Referring now to the letters of reference placed upon the drawings:

A, denotes the lock casing provided with an indicating arrow or mark A', adapted to co-ordinate with a plurality of graduations B' upon the edge of a rotatable cap B overlapping the wall of the casing. C, is a centrally disposed bolt rigidly secured at one end to the cap B, provided with a projecting tongue C' which is adapted to rotate in a stepped-counterbore A² formed in the casing. D, denotes a fixed sleeve or tumbler slotted as at D' to receive the tongue C' of the bolt when brought into proper registration therewith. The sleeve or tumbler D is counterbored at its upper end as 110

indicated at D^2 and is provided with a vertical slot D^3 in the counterbored end. E , is a tumbler sleeved in the bore of the fixed sleeve or tumbler D having an enlarged head 5 E' projecting into the counterbored portion of the latter. The enlarged head E' is also provided with a peripheral groove E^2 to receive a drag-spring F having a radially projecting end F' extending into the slot 10 D^3 of the sleeve or tumbler D . E^3 is a segmental lug projecting from the enlarged head E' of the tumbler E adapted to co-operate with a pin G^3 projecting through the enlarged head G' of the tumbler G . E^4 15 is a slot in the tumbler E adapted to receive the tongue C' of the bolt C when brought into proper registration with the groove D' of the sleeve or tumbler D and with the slot G^2 in the tumbler G . F , is another drag-spring lodged in the groove of 20 the enlarged head of the tumbler G ; its radially projecting end F' also extending into the slot D^3 of the sleeve or tumbler D . H , is a driving disc sleeved upon the bolt C 25 and provided with a lug or key H' projecting into a key-way C^2 in the bolt that the disc may be rotated when the latter is turned. H^2 is a segmental lug projecting from the driving disc adapted to engage 30 the upper end of the pin G^3 projecting above the tumbler G , whereby the latter may be rotated to bring the slot G^2 of the tumbler G and the slot E^4 of the tumbler E into registration with the slot D' of the sleeve or 35 tumbler D upon a manual predetermined rotation of the cap B , obtained through the co-ordination of the graduations on the cap and lock casing. N , denotes a nut screwed into the tapped upper end of the lock casing 40 A , counterbored on its under face to receive the driving disc H , its surrounding outer edge bearing upon the edge of the sleeve or tumbler D , to secure the latter against dislodgment or displacement. N' is a pin 45 extending through the wall of the lock casing into the nut to secure the latter when in position.

In order that the cap B may be readily rotated upon the end of the lock casing it may 50 be fitted with a slidable crank arm I , fitted with a knob I' , the arm being slotted as at I^2 for the passage of a pin B^2 , whereby it is secured to the end of the cap;—and when not employed for rotating the cap it may 55 be pushed out of the way and in alignment with the end of the cap. J , is a washer sleeved upon the end of the bolt having a lug J' extending into the key-way C^2 of the bolt that it may be rotated thereby. J^2 is a 60 raised portion struck from the body of the metal adapted to enter any of the series of serrations A^3 formed in the end of the lock casing. The serrations A^3 co-ordinate with the graduations B' and A' on the lock 65 casing and cap. The serrations are separ-

ated at one point by a blank portion A^4 , as indicated in Figure 11 to provide a "starting point" for adjusting the tumblers. K , is a spring sleeved upon the end of the bolt D adapted to bear upon the washer J and 70 against the inner face of the cap B . Projecting from the closed end of the casing A is a lug A^5 to which one end of a chain L is secured by riveting the lug A^5 to the end link as indicated in Figure 14. M , is a removable plunger having a projecting stem M' riveted to the end link at the opposite end of the chain. The plunger M is provided at its free end with a peripheral groove M^2 to receive the end of the bolt C 75 when the latter is in "locked" position as shown in Figure 2.

Having now indicated the several parts by reference letters the construction and operation of the device will be readily understood. 80

While the embodiment of the device shown in the drawings is especially adapted for securing a spare tire to a supporting frame it will be apparent that it may be employed 90 as an ordinary door lock or as a lock for other purposes for which it may be adapted.

In describing its operation it will first be assumed that the bolt is in its unlocked position as indicated in Figure 14, the removable plunger M carried by the free end of the chain is then inserted as indicated;—the cap to which the bolt C is attached is then forced inwardly against the action of the spring K , thereby causing the forward end of the bolt to enter the peripheral groove M^2 , at the end of the removable plunger. The cap is then manually rotated to shift the relative positions of the tumblers E and G so that the grooves E^4 and G^2 of the respective tumblers are out of registration with the groove D' in the sleeve D , thus securing the tongue C' of the bolt C against return and in locked position as indicated in Figure 2. When it is desired to unlock the 110 device the tumblers are rotated through the manual operation of the cap B so as to bring the grooves E^4 and G^2 of the respective tumblers into registration with the groove D' of the sleeve or tumbler D that the tongue 115 C' of the bolt C may be forced out of the peripheral groove M^2 by the spring K into the groove D' , E^4 and G^2 of the respective tumblers, this result being effected as will be understood, through the arbitrary adjustment of the graduated cap with reference to the indicating arrow or graduation A' on the wall of the lock-casing. Upon the tumblers being brought into proper registration the spring K forces the cap B outwardly 120 (see Figure 14) carrying therewith the bolt C ,—the tongue C' of the bolt entering the aligned grooves D' , E^4 and G^2 of the respective tumblers, thereby releasing the plunger M , that it may be removed from the casing. 130

125

The adjustment of the tumblers may be effected at night or in the dark by counting the audible "click" resulting from the raised portion J^2 of the washer entering the different serrations as the cap is rotated;—the starting position being determined by the spaced portion A^4 between the serrations, as will be readily understood.

While I have shown an adjustable crank 10 arm I attached to the rotatable cap for the convenient operation of the latter, the arm may be dispensed with and the outer wall of the cap may be "milled" to provide a good gripping surface to assist in its manual operation.

Having thus described my invention what I claim is:

1. In a device of the character described; an enclosing case; a rotatable cap fitted to one end of the case provided with a plurality of graduations adapted to co-ordinate with indicating means on the enclosing case; a manually rotatable and longitudinally movable bolt secured to the cap having a laterally extending tongue; a washer keyed to the bolt having a lug adapted to engage any of a plurality of serrations formed in the wall of the enclosing case; a spring located between the rotatable cap and the washer; a plurality of rotatable co-ordinating tumblers housed in the case severally provided with slots adapted to be brought into registration with each other; means carried by the bolt adapted to rotate one of the tumblers and thereby the co-operating tumblers, whereby the slots of the respective tumblers may be brought into registration with each other to receive the tongue projecting from the bolt, and a co-acting member adapted to receive the end of the bolt when longitudinally actuated, whereby a locked condition may be obtained.
2. In a device of the character described; an enclosing case; a rotatable cap fitted to one end of the case provided with a plurality of graduations adapted to co-ordinate with a registering graduation upon the case; a manually rotatable and longitudinally movable bolt secured to the cap provided with a laterally extending tongue; a washer keyed to the bolt having a lug adapted to engage any of a plurality of serrations formed in the wall of the enclosing case; a helical spring located between the wall of the cap and the washer; a plurality of rotatable cylindrical tumblers nested together within the case and severally provided with slots adapted to be brought into registration to receive the tongue of the bolt; a drag-spring lodged in a peripheral groove formed in the wall of the respective tumblers adapted to secure said tumblers against accidental rotation, and means carried by the bolt adapted to effect the rotation of the tumblers, whereby the slots in said tumblers
3. In a device of the character described; an enclosing case; a rotatable cap fitted to one end of the case provided with graduations adapted to co-ordinate with indicating means on the enclosing case; a manually rotatable and longitudinally slidable bolt secured to the cap and having a laterally extending tongue; a washer keyed to the bolt having a lug adapted to engage any of a plurality of serrations formed in the wall of the enclosing case; a sleeve slotted to receive the tongue of the bolt having a counterbore at one end; a plurality of tumblers nested together in the bore of the sleeve provided with enlarged heads housed within the counterbore of the sleeve; a drag-spring mounted in a peripheral groove in the enlarged head of each tumbler having one end of each spring extending into a slot formed in the counterbored end of the sleeve; a disc carried by said bolt adapted to engage means carried by the enlarged head of one of said tumblers, whereby the tumbler may be rotated with the bolt; means carried by the heads of the respective tumblers adapted to be acted upon by the first named tumbler, whereby they may be severally turned to cause the slots in the respective tumblers to register with each other and with the tongue carried by the bolt, and resilient means for forcing said bolt outwardly, whereby the tongue of said bolt may enter the aligned slots in the tumblers and also force the lug of said washer to engage the serrations in the wall of the enclosing case.
4. In a device of the character described, an enclosing case, a rotatable cap slidably fitted on the exterior of one end of the case and provided with graduations adapted to co-ordinate with indicating means on the enclosed case, a manually rotatable and longitudinally movable bolt secured to the cap and having a laterally projecting tongue, a spring housed within the cap and arranged to be compressed by the same for urging the tongue and the cap outwardly, means carried by the bolt adapted to engage any of a plurality of serrations formed in the enclosing case, a member adapted to receive the end of said bolt, whereby a locked relation may be obtained; a plurality of nested rotatable coordinating tumblers housed in the case adapted to secure the bolt in its locked relation with the bolt receiving member, said tumblers being severally provided with slots adapted to be brought into registration with each other upon a predetermined arbitrary rotation of the bolt, whereby the bolt may be released from its locked relation with the bolt receiving member, and means carried

may be brought into registration with each other upon an arbitrary predetermined rotation of the tumblers through the co-ordination of said graduated cap and the enclosing case.

70

3. In a device of the character described; an enclosing case; a rotatable cap fitted to one end of the case provided with graduations adapted to co-ordinate with indicating means on the enclosing case; a manually rotatable and longitudinally slidable bolt secured to the cap and having a laterally extending tongue; a washer keyed to the bolt having a lug adapted to engage any of a plurality of serrations formed in the wall 80 of the enclosing case; a sleeve slotted to receive the tongue of the bolt having a counterbore at one end; a plurality of tumblers nested together in the bore of the sleeve provided with enlarged heads housed within the counterbore of the sleeve; a drag-spring mounted in a peripheral groove in the enlarged head of each tumbler having one end of each spring extending into a slot formed in the counterbored end of the sleeve; a disc carried by said bolt adapted to engage means carried by the enlarged head of one of said tumblers, whereby the tumbler may be rotated with the bolt; means carried by the heads of the respective tumblers adapted to be acted upon by the first named tumbler, whereby they may be severally turned to cause the slots in the respective tumblers to register with each other and with the tongue carried by the bolt, and resilient means for forcing said bolt outwardly, whereby the tongue of said bolt may enter the aligned slots in the tumblers and also force the lug of said washer to engage the serrations in the wall of the enclosing case.

by the bolt adapted to rotate one of the tumblers and thereby the cooperating tumblers to effect either the registration of the slots in said tumblers or the disarrangements 5 of the same with reference to each other.

5. In a device of the character described an enclosing case having a plurality of serrations, a rotatable cap slidably fitted on the exterior of one end of the case and covering 10 said serrations and movable longitudinally of the case and provided with graduations adapted to coordinate with indicating means on the enclosing case, a manually rotatable and longitudinally movable bolt secured to 15 the cap and having a laterally extending tongue, means carried by the bolt adapted to engage any one of the said serrations, a member adapted to receive the end of said bolt, whereby a locked relation may be obtained 20 in connection therewith, a plurality of nested rotatable coordinating tumblers housed in the case and adapted to secure the bolt in its locked relation with the bolt receiving member, said tumblers being severally provided with slots adapted to be brought 25 into registration with each other upon a predetermined arbitrary rotation of the bolt, whereby the bolt may be released from its locked relation with the bolt receiving member; and means carried by the bolt adapted to rotate one of the tumblers and thereby the cooperating tumblers to effect 30 registration of the slots in said tumblers, said spring being adapted to release the rotatable and longitudinally movable bolt from engagement with the bolt receiving member upon the slots in the several tumblers registering with the tongue of said bolt.

40 6. In a device of the character described; an enclosing case provided with a rotatable cap fitted to the end of the case; a slideable crank arm fitted to the cap to facilitate the rotation of the latter; a manually rotatable and longitudinally movable bolt secured to 45 the cap having a laterally extending tongue; means carried by the bolt adapted to engage a plurality of serrations formed in the enclosing case; a member adapted to receive the end of the bolt, whereby a locked relation may be obtained with the latter; a plurality of nested rotatable co-ordinating tumblers housed in the case adapted to secure the bolt in its locked relation with the bolt 50 receiving member, said tumblers being severally provided with slots adapted when brought into registration with each other to release said bolt receiving member and means carried by the bolt adapted to rotate one of the tumblers and thereby the co-operating tumblers to effect registration or disarrangement of the slots in the several tumblers.

60 7. In a device of the character described, an enclosing case, a hollow rotatable cap fitted on the exterior of one end of the case

and slideable longitudinally thereof, a rotatable and longitudinally movable bolt secured to the cap and having a laterally extending tongue, a coiled spring housed within the cap and disposed around the bolt for urging the 70 same and the cap outwardly, a plurality of nested rotatable cooperating tumblers housed in the case and provided with slots adapted to be brought into registration to receive the tongue of the bolt, means carried by the bolt 75 and adapted to rotate the tumblers, a removable member adapted to enter the case and provided with a peripheral groove to receive the end of the bolt, and a chain linked to the case and to the said removable member. 80

85 8. In a device of the character described, a case, a rotatable cap slidably fitted on the exterior of the case and movable longitudinally thereof and provided with a plurality of graduations adapted to coordinate with an indicating mark on the case, a bolt secured to the cap adapted to be rotated and longitudinally shifted through manual operation of the cap, means carried by the bolt and adapted to engage any of a plurality of serrations formed in the wall of the case, a plurality of rotatable coordinating tumblers nested together within the case and severally provided with slots, means also carried by the bolt and adapted to act upon the tumblers, whereby the respective tumblers may be shifted into and out of registration with the tongue of the bolt, resilient means housed within the said cap and arranged to be compressed by the same for urging the cap and the bolt outwardly, and means adapted to receive the end of the bolt to effect a locked relation between the parts upon manually shifting the bolt into engagement with said last named means. 95

100 9. In a device of the character described, a case provided at one end with a plurality of serrations, a hollow rotatable cap fitted on the exterior of the said end of the case and covering the said serrations and provided with a plurality of graduations adapted to coordinate with an indicating mark on the case, a bolt secured to the cap and adapted to be rotated and longitudinally shifted within the case through the manual operation of the cap, means carried by the bolt and adapted to engage the serrations in the end of the case, a spring housed within the cap and interposed between the said means and the cap for urging the said cap and the bolt outwardly, a plurality of rotatable coordinating tumblers nested together within the case and severally provided with slots, means also carried by the bolt and adapted to act upon the tumblers, whereby the slots of the respective tumblers may be shifted into and out of registration with the tongue of the bolt, said spring being adapted to move the tongue of the bolt into the slots of the tumblers when the same are brought into 115 120 125 130

registration therewith, and means to receive the end of the bolt to effect a locked relation between the parts upon manually shifting the bolt into engagement with the said last mentioned means.

10. In a device of the character described; an enclosing case; a rotatable cap fitted to the case provided with a plurality of graduations adapted to coordinate with an indicating mark on the enclosing case; a bolt secured to the cap having a laterally extending tongue, adapted to be manually rotated and longitudinally shifted within the enclosing case; means carried by the bolt 15 adapted to engage any of a plurality of serrations formed in the wall of the enclosing case; a plurality of rotatable co-ordinating tumblers nested together within the case severally provided with slots; means also 20 carried by the bolt adapted to act upon the tumblers, whereby the slots of the respective tumblers may be forced into or out of registration with the tongue of the bolt; a removable plunger provided with a peripheral

groove to receive the end of the bolt, and a chain connecting the plunger and enclosing case.

11. In a device of the character described, an enclosing case, a rotatable cap fitted on the case and slidably longitudinally thereof, a spring housed within the cap and arranged to urge the same outwardly and adapted to be compressed by the cap, a bolt secured to the cap and having a laterally extending tongue and rotated with the cap and also moving longitudinally with the same, a plurality of tumblers nested together within the case and having slots, and means carried by the bolt and adapted to act upon the tumblers, whereby the slots of the respective tumblers may be moved into and out of registration with the tongue of the bolt.

In testimony whereof, I sign this specification in the presence of two witnesses

PAUL SZYDLOWSKI.
